UNITED STATES PATENT OFFICE.

WILLIAM A. FECKLEY, OF DELTA, IOWA.

BEDSTEAD.

1,301,240.

Specification of Letters Patent. Patented Apr. 22, 1919.

Application filed October 23, 1918. Serial No. 259,307.

To all whom it may concern:

Be it known that I, WILLIAM A. FECKLEY, a citizen of the United States, residing at Delta, in the county of Keokuk and State 5 of Iowa, have invented certain new and useful Improvements in Bedsteads, of which the following is a specification.

This invention relates to bed steeds, and more particularly to those designed for use 10 by sick people.

The object of the invention is to provide a bed stand having a head rest whereby the occupant may be supported at any desired angle.

15 Another object is to provide a simple and efficient device of this character which may be removed if desired or collapsed and folded out of the way when not in use, being allowed to remain connected with the 20 bed stand.

With the foregoing and other objects in view, which will appear as the description proceeds, the invention resides in the combination and arrangement of parts and in 25 the details of construction hereinafter described and claimed, it being understood that changes in the precise embodiment of the invention herein disclosed may be made within the scope of what is claimed without departing from the spirit of the invention.

In the accompanying drawings:—

Figure 1 represents a side elevation of a bed stand constructed in accordance with this 35 invention with parts broken out for convenience in illustration,

Fig. 2 is a front elevation of the head member of the bed stand taken from the inside with parts broken out and in section,

40 Fig. 3 is a front elevation of the head rest employed in connection with this bed stand,

Fig. 4 is an enlarged detail vertical section through one of the posts of the head member of the bed,

45 Fig. 5 is a detail perspective view of the keeper used in connection with this improved bed stand,

Fig. 6 is a detail sectional view showing a portion of one of the posts of the head 50 member and the parts connected therewith, and

Fig. 7 is a detail perspective view of a portion of the head member.

In the embodiment illustrated, the bed stand embodying this invention is shown 55 made of metal and comprises a head member 1, foot member 2, connected by side rails 3. A rod 4 is rotatably mounted in the posts 7 of the head member 1, said posts being hollow and the ends of said rod extending into them. Each end of this rod is provided with a pinion 6, and the portion of the rod outside the post 7 is made angular as shown at 5 for the interlocking engagement of catch members 12 pivotally mounted 65 on the posts 7 above the rod 4 as is shown clearly in Figs. 2 and 6.

The posts 7 at their lower ends are slotted longitudinally on their inner faces as shown 70 at 8 and arranged within said posts are rack bars 9 which are designed to reciprocate in the posts and the teeth of which mesh with the pinions 6 carried by the rod 4.

The lower ends of the rack bars 9 are provided with open longitudinally extending 75 slots 10 with a pin or rod 11 extending transversely across this slotted end and which is designed for connection with the lower ends of links 17 of the head rest 20 presently to be described.

Secured to the side rails 3 at points spaced some distance from the head boards or member 1, are keepers 13 shown slotted longitudinally at 15 and having apertured lugs 14 for fastening them to the side rails. These 85 keepers are disposed longitudinally on said side rails and the slots 15 thereof are designed to receive the lower free ends 16 of side bars 21 of the head rest 20 as is shown clearly in Fig. 1.

The head rest 20 as shown is made rectangular in form and pivotally connected with the upper corners thereof are the links or bars 17, the lower ends of which are curved outwardly and slotted longitudinally 95 at their terminals as shown at 19, these slots being open to provide for their engagement with the pins or cross rods 11 carried by the rack bars 9. By so curving and slotting the ends 18 of the links 17 they may have a 100 hooklike engagement with the pins 11 to provide for their ready connection and disconnection when desired.

The side bars 21 of the head rest are connected near their lower ends by a cross bar 105 22 below which the bars 21 are given a

twist as shown at 23 so that the ends 16 thereof will be disposed edgewise for insertion through the slots 15 in the keepers 13, said side bars being preferably made of 5 strap iron as shown.

In the use of this head rest, when it is desired to elevate it, the hooks 12 are first disengaged from the rod 4 and then the cross bar at the upper end of the head rest is 10 grasped and the rest swung upward, the ends 16 which are inserted in the keepers operating as pivots and the ends 18 of the links 17 being engaged with the rack bars 9 will cause said rack bars to move upwardly 15 and consequently turn the pinions 6 and the rod 4 on which they are mounted. When the rest has been positioned at the desired angle, it is held in this position by engaging the catches 12 with the angular portions 5 of 20 the rod 4, which holds this rod against turning and consequently prevents the downward or upward movement of the rack bars.

If it is not desired to use this head rest, the slotted ends 19 of the links 17 may be 25 disengaged from the pins 11 and said links folded inwardly into substantially parallel position with the side bars 21. The head rest may then be lowered so that the side bars 21 thereof will rest on and lie parallel 30 with the side rails 3 of the bedstead. When so positioned, obviously, the head rest will be out of the way and will afford no inconvenience to the user of the bed.

It is of course understood that the rest 35 may be entirely removed by disengaging the curved ends 16 of the side bars 21 from the keepers 13 and that they may be quickly applied again when desired for use.

It will be obvious that a bedstead constructed as described will not be marred in 40 appearance by the application of this head rest and when the head rest is removed the only evidence of its having been on the bedstead will be of the slots in the posts 17 and 45 the keepers 13 on the side rails.

From the foregoing description, taken in connection with the accompanying drawings, the advantages of the construction and of the method of operation will be readily apparent to those skilled in the art to which 50 the invention appertains and while I have described the principle of operation of the invention together with the device which I now consider to be the best embodiment 55 thereof, I desire to have it understood that the device shown is merely illustrative and that such changes may be made as are within the scope of the claimed invention.

Having thus fully described my inven-

tion, what I claim as new and desire to secure by Letters Patent, is:—

1. The combination with a bedstead having a head member equipped with hollow legs longitudinally slotted on their inner faces, rack bars mounted to slide in said legs 65 and having transversely arranged pins carried thereby, a head rest mounted for pivotal movement on said bedstead at a point spaced from said head member, and links connecting said head rest with said rack bars, 70 said links extending through the slots in the legs and having their free ends bent laterally and forwardly and equipped with longitudinal slots, the lower wall of each slot being open for the entrance of one of said pins, and 75 means for locking said rack bars in adjusted position.

2. The combination with a bedstead having a head member equipped with hollow legs, said legs being longitudinally slotted, 80 rack bars mounted to slide in said legs and having bifurcated lower ends, pins spanning the space between said furcations, a head rest mounted for pivotal movement on said bedstead at a point spaced from the head 85 member, links connecting said head rest with said rack bars, said links extending through the slots in the legs, and having open slotted ends for engagement with said pins, a rod having a pinion meshing with one of said 90 rack bars, and means for locking said rod whereby the head rest is held in adjusted position.

3. The combination with a bedstead having a head member provided with hollow 95 legs slotted longitudinally on their inner faces, rack bars mounted to reciprocate longitudinally in said legs, a rod rotatable in said head member with its ends extending into the legs thereof and equipped with 100 pinions meshing with said rack bars, said rod being provided outside said legs with angular portions, catches carried by said head member for engaging the angular portions of the rod whereby it is locked against 105 rotary movement, a head rest pivotally connected with said bedstead at points spaced from the head member thereof, and links carried by said head rest and detachably engaged with said rack bars, said links extending through the slots in said legs. 110

In testimony whereof I affix my signature in presence of two witnesses.

WILLIAM A. FECKLEY.
